UNITED STATES PATENT OFFICE.

GEORGES ALBERT BUSSAC, OF PARIS, FRANCE.

STEAM GENERATOR.

Application filed July 20, 1920. Serial No. 397,692.

To all whom it may concern:

Be it known that I, GEORGES ALBERT BUSSAC, a citizen of the Republic of France, residing at 17 rue de Rome, Paris, Seine, France, have invented new and useful Improvements in Steam Generators, of which the following is a specification.

The present invention relates to a steam-boiler for high pressures and great evaporative capacity and it is characterized by the special combination of the various elements of the boiler and by a special arrangement of the tubes within which the water is evaporated.

15 The invention is shown diagrammatically and by way of example in the accompanying drawings in which:

Figure 1 is a longitudinal section through one of the water-tubes of the boiler.

20 Figure 2 is a section along line 2—2, Fig. 1 to a larger scale.

Figure 3 is a section along line 3—3, Fig. 1 to a larger scale.

Figure 4 is a longitudinal section of the 25 boiler as a whole.

Figure 5 is a cross-section thereof and

Figure 6 is a cross-section of the nest of tubes.

Each water-tube (Figs. 1, 2 and 3), known 30 as auto-circulatory, consists of an evaporating tube proper or external evaporating tube 1 and of a concentric or feed tube 2 of smaller diameter, which is open at both ends and can consequently be easily examined and 35 withdrawn through the hand-holes 3 in the upper headers 11 and lower headers 15 to be described below.

The feed-tube 2 is centered at the top by 40 means of a spider formed by cutting tongues 4 in the metal of the tube, these tongues being then bent outwardly and being prolonged beyond the exterior diameter of the tube 1. The lower edge of these tongues is notched, near the end and the notches engage and seat upon the upper edge of the tube 1 so as to seat and centre the tube 2.

45 Centering of the lower portion of the tube is effected by means of a spider 5 forced into the lower portion of the water-tube 1 and 50 flush with its extremity. This spider can be extracted by means of a suitable tool passed

through the hand-hole 3 of the lower header. Tongues 6 are cut in the spider 5 and are bent round inwardly so as to effect centering of the tube 2.

55 This arrangement of water-tube constitutes one of the characteristics of the invention, and it is obvious that it could be applied to any existing water-tube boiler. It has many advantages over either water-tubes 60 with closed bottoms in which sediment accumulates, or over water-tubes which are open at both ends and without internal tubes, in which the circulation of the water and steam are not separated.

65 A general description of the boiler will now be made, the course of the water being followed as far as possible from its entry into the boiler to its exit in the form of steam.

70 Two feed-water headers 7, 7¹ are placed longitudinally of the boiler and at the top, thereof. These headers consist of steel boxes having the form of parallelepipeds of square section. Baffles 8, 8¹ are arranged in these headers and access can be had to them 75 through the hand-holes. These baffles effect the preliminary settling of any mud or impurities which may be introduced by the feed-water. A blow-off cock 9, 9¹ for each header enables this mud and the like to be 80 got rid of. In order to permit of this preliminary settling, the feed takes place at 10^a at the bottom of the feed-headers 7, 7¹ at points remote from the communication tubes 10, 10¹ to be described below.

85 Transversely to the feed headers 7, 7¹ and between them is arranged a series of steel chambers of rectangular cross-section which form the upper collectors of water and steam 11, 11¹, 11² . . . 11ⁿ, the median horizontal 90 plane of which constitutes the plane of the water in the boiler. These collectors have the characteristic that they are the only ones in the whole boiler which are of rectangular cross-section, they are given this form in 95 order that they may have a sufficient steam-space.

95 The upper collectors for water and steam 11, 11¹, 11² . . . 11ⁿ are in communication on the one hand with the feed water headers 7, 7¹ 100 by a double series of communicating tubes 10, 10¹, 10² . . . 10ⁿ on one side and 10', 10'¹

10² . . . 10ⁿ on the other side, and on the other hand with the longitudinal collectors 13, 13¹, which receive the steam and will be described below, by a double series of communicating tube 12, 12¹, 12² . . . 12ⁿ on one side and 12', 12', 12' . . . 12'ⁿ on the other side.

5 All of these communicating tubes are well covered with heat-insulating material and can easily be dismounted for the purpose of examining and, if necessary, repairing the boiler.

10 The lower walls of the collectors 11, being in direct contact with the gases of combustion form heating surfaces. It results 15 from the small extent of the peripheral surface of these collectors and also from the fact that the removable heat-insulated panels 14 isolate them from the outer air, that the temperature of their upper walls 20 remains above that of the steam which they contain. The small quantity of water due to priming which may have been entrained by the passage of steam through the liquid is therefore evaporated on contact with these 25 walls and the steam which passes thence to the distributing headers, to the super-heater and to the engine is practically dry.

30 The upper collectors 11, 11¹, 11² . . . 11ⁿ for steam and water are connected to the lower corresponding sediment collectors 15, 15¹, 15² . . . 15ⁿ, constituted by square steel boxes, by means of auto-circulatory tubes 1, similar to those described and shown in Figures 1, 2 and 3. The series of auto-circulatory tubes is inclined from front to rear 35 downwardly for the purpose, on the one hand, of facilitating the normal action of the current of gases on the tubes and, on the other hand, of enabling the grate of the boiler to be fitted as far as possible in the horizontal projection of the nest of tubes, so as to reduce the space occupied by the whole.

40 Each series of auto-circulatory tubes is set 45 in staggered relation to its neighbour, as shown in Figure 6. It should be remarked that the upper collectors 11 and lower ones 15 are perfectly rectilinear and that all the tubes 1 are expanded into the collectors. 50 This rectilinear arrangement of the collectors constitutes one of the characteristics of the invention; in that it enables the tubes to be staggered without necessitating the use of vertical collectors, or collectors inclined towards the vertical.

55 It should further be pointed out that the lower collectors are at a slight distance apart one from the other, which prevents the accumulation of soot and facilitates 60 cleaning, which is a great advantage in view of the fact that soot causes condensation and pitting of the outside of the tubes, which are drawbacks to be avoided.

65 Owing to the special arrangement of the collectors 11, the steam formed in the an-

to the lateral steam collectors 13, 13' is generated uniformly on the entire surface of the plane of water of these collectors.

The lower collectors 15, 15¹ . . . 15ⁿ are arranged parallel to the upper collectors 11, 11¹ . . . 11ⁿ and owing to the fact that they are arranged just at the mouths of the feed tubes 2 and at the exact spot where the water begins to be transformed into steam and precipitates the salts of lime contained therein, they form so many sediment collectors of perfect efficiency; their large total volume permits of collecting with certainty all sediment and thereby protects the boiler against scale, which is so much to be feared, and which no other device hitherto designed has been able to do with the same efficiency.

Beneath the lower collectors of sediment 15, 15¹ . . . 15ⁿ are arranged two drainage collectors 16, 16¹ communicating with each 85 of the collectors 15, 15¹ . . . 15ⁿ at the two extremities; each of these drainage collectors 16, 16¹ is provided with a blow-off cock 17, 17¹ which permits of discharging the salts and sediment precipitated.

The steam generated in the upper collectors 11, 11¹ . . . 11ⁿ is conducted by a double series of communication tubes 12, 12¹, 12² . . . 12ⁿ on one side and 12', 12', 12' . . . 12'ⁿ on the other side into steam-collectors 13, 13¹ arranged one on each side of the boiler above the feed-headers 7, 7¹. These steam collectors communicate with the feed headers 7, 7¹ by means of tubular connections generally known as nipples 23, 23¹ which are expanded into the headers at 90 two points very close together so as to do away with the effects which might result from a slight difference in dilatation between the two collectors. This communication is for the purpose of establishing equality of pressure between these two portions of the boiler and, furthermore, to permit of the return to the feed-headers of the water, due to priming, which might have 100 been deposited upon the inner walls of the steam collectors, in spite of the drying effect spoken of above.

The steam collectors 13, 13¹ which are in communication with the upper collectors of 115 water and of steam 11, 11¹, 11² . . . 11ⁿ by way of tubes 12 . . . 12ⁿ and 12' . . . 12'ⁿ are carefully covered with heat-insulating material, as are also the feed-water headers 7, 7' with which they are arranged in pairs, 120

The lateral steam collectors 13, 13' communicate by the intermediary of the nipples 24, 24' with the extremities of a main collector of saturated steam 18 which is also heat-insulated and carries the safety-valves, 125 pressure gauges and the flanges for connecting the pipes taking the steam to the superheater 19. The dilatation of this main collector, transmitted by the nipples 24, 24' 130

65 . . . 12'ⁿ is absorbed

by the communicating tubes 12 . . . 12° and 12' . . . 12".

The circulation of the gases through the nest of tubes is effected, as in the case of 5 most multitubular boilers, by the help of interposed baffle-plates 20, 21, 22. The whole boiler is mounted on the furnace enclosed in suitable masonry.

This arrangement of boiler presents numerous advantages, it contains no rivets, no 10 caulked joints nor stays and it consists entirely of parts of small section, and therefore of great resistance, which communicate with each other by tubes fixed in place by 15 expansion.

Danger of explosions is diminished and they are of less serious a character than is the case with boilers having cylindrical bodies of large diameter, or having headers 20 involving large flat-surfaces in one piece, in view of the high pressures it is intended to use.

Each of the essential functions is ensured by means of a double set of parts, thereby 25 giving the boiler great reliability.

The mud is separated preliminary at the entrance of the water to the boiler proper, the water being settled in feed-water headers which are heat-insulated and isolated 30 from the products of combustion.

The scale-producing salts are precipitated at the points where they form, that is to say at the base of the vaporizing tubes and the sediment is received in a plurality of collectors which can be easily discharged and 35 examined.

The arrangement of the auto-circulatory tubes, each consisting of a water-tube and a feed tube creates a very active circulation 40 which enables very high evaporation to be obtained.

The evaporating surface is extremely divided up and the steam is generated uniformly over this entire evaporating surface 45 or water-surface.

The steam is dried automatically by being projected against the walls of the upper collectors, which walls are very close together and are raised by conductivity to a temperature 50 higher than that of the steam produced.

The steam is quickly separated from the liquid producing it, as it passes immediately into collectors which are not in contact with the feed-water and whose cross-section 55 decreases, thereby accelerating the speed of the passage of the steam in proportion as it travels away from the source of its production.

The tubes are perfectly staggered with 60 relation to the circulation of the gases, this result being obtained without corrugated collectors nor headers nor cylindrical bodies of large diameter arranged one behind the other.

65 The invention has been described in de-

tail purely by way of explanation but in no way limitatively and it is obvious that the details might be modified without departing from the spirit thereof, which is to be understood in its broadest sense.

I claim:

1. A steam-boiler comprising upper longitudinal feed water headers, upper and transverse collectors of water and steam, communicating means between said headers and collectors, sediment collectors arranged at the bottom of the boiler, vaporizing tubes connecting said water and steam collectors to said sediment collectors and comprising each an outer tube for the ascending mixture of steam and water and an inner tube for the descending water, upper longitudinal steam collectors connected to said steam and water collectors, and a main steam collector connected to said upper longitudinal steam 70 collectors. 75

2. A steam-boiler comprising upper longitudinal feed water headers, upper and transverse collectors of water and steam, communicating means between said headers and collectors, sediment collectors arranged in spaced relation at the bottom of the boiler, vaporizing tubes connecting said water and steam collectors to said sediment collectors, and comprising each an outer tube for the 90 ascending mixture of steam and water and an inner tube for the descending water, upper longitudinal steam collectors connected to said steam and water collectors, and a main steam collector to said upper longitudinal steam 95 collectors. 100

3. A steam-boiler comprising upper longitudinal feed water headers, baffles arranged at the water-inlet to said headers, upper and transverse collectors of water and steam, communicating means between said headers and collectors, sediment collectors arranged at the bottom of the boiler, vaporizing tubes connecting said water and steam collectors to said sediment collectors and comprising each an outer tube for the ascending mixture of steam and water and an inner tube for the descending water, upper longitudinal steam collectors connected to said transverse steam and water collectors and a main steam 105 collector connected to said upper longitudinal steam collectors. 110

4. A steam boiler comprising upper longitudinal feed water headers, upper and transverse steam and water collectors, upper and longitudinal steam and water collectors, sediment collectors arranged at the bottom of the boiler and removable communication tubes connecting said feed-water headers to said steam and water collectors. 120

5. A steam boiler comprising upper longitudinal feed water headers, upper and transverse collectors of steam and water of rectangular cross section, communicating means between said headers and collectors, 125 130

- sediment collectors arranged at the bottom of the boiler and spaced apart, and double vaporizing tubes between the sediment collectors and the steam and water collectors.
5. A steam-boiler comprising upper longitudinal feed water-headers, upper and transverse collectors of steam and water of rectangular cross-section, said collectors being heated by metallic conductivity, communicating means between said headers and collectors, sediment collectors arranged at the bottom of the boiler and spaced apart and double vaporizing tubes between the sediment collectors and the water and steam collectors.
10. A steam-boiler comprising upper longitudinal feed water headers, upper and transverse steam and water collectors, upper and longitudinal steam and water collectors, connecting means between said feed-water headers and said collectors, sediment collectors arranged at the bottom of the boiler and double vaporizing tubes between said sediment collectors and said steam and water collectors.
15. A steam boiler comprising upper longitudinal feed water headers, upper and transverse collectors, upper and longitudinal collectors, communicating means between the headers and collectors, sediment collectors arranged at the bottom of the boiler, double vaporizing tubes between the sediment collectors and the water and steam collectors, drainage collectors connecting the extremities of said sediment collectors and blow-off cocks fitted on said drainage collectors.
20. A steam-boiler comprising upper feed-water headers, upper and transverse steam and water collectors, upper and longitudinal steam and water collectors, sediment collectors arranged at the bottom of the boilers, double vaporizing tubes between said headers and steam and water collectors respectively, said sediment collectors being spaced apart for the purpose set forth.
25. A steam-boiler comprising upper feed-water headers, upper and transverse steam and water collectors, upper and longitudinal steam and water collectors, sediment collectors arranged at the bottom of the boiler, and double vaporizing tubes inclined downwardly from front to rear between said sediment collectors and said steam and water collectors.
30. A steam-boiler comprising upper feed-water headers, upper and transverse steam and water collectors, upper and longitudinal steam and water collectors, sediment collectors arranged at the bottom of the boiler and double vaporizing tubes between the sediment collectors and said steam and water collectors.
35. A steam-boiler comprising upper feed-water headers, upper and transverse steam and water collectors, upper and longitudinal steam and water collectors, sediment collectors arranged at the bottom of the boiler, and double vaporizing tubes inclined downwardly from front to rear connecting said sediment collectors to the upper steam and water collectors.
40. A steam-boiler comprising upper feed-water headers, upper and transverse steam and water collectors, upper and longitudinal steam and water collectors, connecting means between said feed-water headers and the collectors, sediment collectors arranged at the bottom of the boiler and double vaporizing tubes inclined downwardly from front to rear connecting said sediment collectors to the upper steam and water collectors.
45. A steam-boiler comprising upper feed-water headers, upper transverse and longitudinal steam and water collectors, connecting means between said feed-water headers and the collectors, sediment collectors arranged at the bottom of the boiler and double vaporizing tubes inclined downwardly from front to rear connecting said sediment collectors to the upper steam and water collectors.
50. A steam-boiler comprising upper feed-water headers, upper transverse and longitudinal steam and water collectors, connecting means between said feed-water headers and the collectors, sediment collectors arranged at the bottom of the boiler and double vaporizing tubes inclined downwardly from front to rear connecting said sediment collectors to the upper steam and water collectors.
55. A steam-boiler comprising upper feed-water headers, upper transverse and longitudinal steam and water collectors, connecting means between said feed-water headers and the collectors, sediment collectors arranged at the bottom of the boiler and double vaporizing tubes inclined downwardly from front to rear connecting said sediment collectors to the upper steam and water collectors.
60. A steam-boiler comprising upper feed-water headers, upper transverse and longitudinal steam and water collectors, connecting means between said feed-water headers and the collectors, sediment collectors arranged at the bottom of the boiler and double vaporizing tubes, arranged in staggered relation, and inclined downwardly from front to rear connecting said sediment collectors to the upper steam and water collectors.
65. A steam boiler, comprising upper feed-water headers, upper transverse and longitudinal steam and water collectors, connecting means between said feed-water headers and said collectors, sediment collectors arranged at the bottom of the boiler and double vaporizing tubes, arranged in staggered relation, and inclined downwardly from front to rear connecting said sediment collectors to the upper steam and water collectors.
70. A steam-boiler comprising upper feed-water headers, upper and transverse steam and water collectors, upper and longitudinal steam and water collectors, sediment collectors arranged at the bottom of the boiler and double vaporizing tubes, arranged in staggered relation, and inclined downwardly from front to rear connecting said sediment collectors to the upper steam and water collectors.
